SHOCKPROOF ELECTRICAL DEVICE AND A
SHOCK ABSORBING AND DISTRIBUTING
MEANS THEREFORArthur C. Blakeman, North Arlington, N. J., as-
signor to Westinghouse Lamp Company, a cor-
poration of Pennsylvania

Application September 2, 1931, Serial No. 560,738

5 Claims. (Cl. 250—35)

This invention relates to electrical devices and more particularly to tubes of this character having relatively heavy electrodes or other elements generally supported by, located within and spaced from the interior walls of a readily frangible envelope and/or sleeve, as for example, X-ray or other tubes especially adapted for general radiographic purposes.

In order that the description of my invention may be clear and concise and so that its advantages may be readily apparent, I will describe my invention in conjunction with an X-ray tube.

One form of X-ray tube comprises a cylindrical glass envelope having one of its ends of a bulbous or hemispherical contour and having at the other end a reentrant tube whose diameter is substantially less than the corresponding dimension of the envelope. Along about the middle third length of the envelope is a second reentrant tube, with one of its ends firmly secured to the envelope. Disposed above the free end of the second reentrant tube is a suspended metallic screen housing a cathode and having its outer surface spaced from the inner wall of the envelope. The inner end of the first mentioned reentrant tube has firmly sealed thereto a metallic sleeve adapted to support an anode which passes therethrough. The anode, being of such lengthwise dimension that its free loaded end is spaced from and within the inner side walls of the metallic screen, has the outer periphery of a substantial portion thereof surrounded by and spaced from the inner wall of the second reentrant tube.

Heretofore the general deficiencies in the physical characteristics in tubes of this character have been appreciated and to some extent eliminated by Ulrey and Ehrke in the manner defined by them in their United States Patent No. 1,715,152 issued May 28, 1929.

Broadly, the means therein described for improving the physical characteristics of a tube of this character consists of a slotted cylindrical resilient means for supporting the anode and metallic screen from the side walls of the reentrant tube and the envelope, respectively. This resilient means consists essentially of a collar or sleeve adapted to fit closely around the member to be supported and further characterized by an outwardly and downwardly extending shoulder integral therewith, and a slotted extended cylinder depending from said shoulder. This resilient means is fixedly secured to the member to be supported by means of stud bolts.

Although this particular means has greatly im-

proved the physical characteristics of these tubes so as to make them more rugged, their manufacture is a costly operation. Moreover, when employing a cylindrical resilient means of this character it is necessary that the outer circumferential dimension of the extended slotted cylindrical portion closely approximate the interior circumferential dimension of that member with which it is to be in frictional contact, otherwise there are a number of line, rather than surface, contacts between the resilient means and the frictional supporting members which is obviously undesirable because of the danger of cracking the supporting member along these lines of contact upon a jarring or shocking of the tube.

As a specific improvement thereover this invention has a number of advantages which will be readily apparent from the description and drawing.

An object of my invention is to provide a rugged electrical tube including a frictional bearing element which may be readily manufactured at a low cost, and may be readily assembled and reclaimed.

Another object of my invention is to provide a resilient means of such construction that it may afford a comparatively large surface contact with a frangible element of an electrical tube.

A further object of my invention is to provide a resilient means adapted to serve as a friction bearing element in an electrical tube in order to render the same more rugged and of such a character that its resiliency is not adversely effected by high temperatures.

In the drawing:

Figure 1 represents a sectional view of an X-ray tube embodying my invention;

Figure 2 represents a sectional view taken along line II—II of Figure 1.

Figure 3 represents a perspective view, with a cross sectional illustration of my improved resilient supporting and shock distributing means embodied in the upper end of an X-ray tube;

Figure 4 represents a sectional view taken along lines IV—IV of Figure 1; and—

Figure 5 represents a perspective view, with a cross sectional illustration of my improved resilient supporting and shock distributing means embodied in one of the reentrant tubes of an X-ray tube.

As shown in Figure 1, the X-ray tube may comprise a transparent, gas tight, cylindrical glass envelope 10, of bulbous or hemispherical contour at one end 11, and having a reentrant tube 12 at its other end. Located above the re-

55

entrant tube 12 and firmly secured to the envelope 10 is a second reentrant tube 13 of substantial length. Above the free end of the second reentrant tube 13 is a nickel-iron screen 14 serving to screen out undesirable X-rays and to house a cathode as at 15. The cathode within the housing is supplied with electrical current by means of the conductors 16 hermetically sealed to the glass envelope and serving to support the metallic screen. The inner end of the reentrant tube 12 has firmly sealed thereto a metallic sleeve 17 which supports an anode 18. This anode 18 extends upwardly in the tube with a substantial portion of its outer surface spaced from and surrounded by the reentrant tube 13, and with its loaded end 19 spaced from and within the metallic sleeve 14.

According to my invention, in order that a tube of this character may be able to withstand shocks without any danger of breaking during the commercial manipulation, transportation and operation thereof, I provide therefor my novel type of resilient means 20 and 21 which are adapted to be employed therewith as a shock distributing and absorbing means. Besides having the above characteristics I prefer that said means are of such a composition that they do not lose their resiliency during the heat treatment of the tube in the course of its manufacture.

For this purpose, the resilient members 20 and 21 are preferably made of resilient molybdenum metal or the like which may be mechanically worked to any desired shape. The resilient elements 20 and 21 are in the form of a plate of substantially flat or slightly curved contour, with a pair of spaced nipples 22 and 23 respectively. The edges of each plate are preferably rounded and two of the oppositely disposed relatively wide marginal portions of the plates 20 and 21 are preferably curved inwardly so that upon assembly a comparatively large surface frictional contact between the plate and its surrounding member may be obtained so as to eliminate all sharp line contacts between the edges of the plate and its surrounding member, and so that the rounded edges of the plate may be in close proximity and preferably in contact with the surrounded member, all being clearly illustrated in Figures 2-4 inclusive.

In further accordance with my invention, the metallic screen 14 and that portion of the anode 18 surrounded by the envelope and the reentrant tube respectively, have on their outer peripheries a plurality of one hundred and twenty degrees spaced rows of depressions 25 and 26 respectively, with the depressions of each of the respective rows spaced from each other a distance equal to the distance between the nipples 22 of the respective plates 20 and 21. These depressions may be readily formed in these members by means of a simple drilling operation and are of such dimensions as to be equal to or slightly greater than the dimensions of the nipples, so that when mounted, the nipples will fit snugly therein.

As shown, there are three spaced plates 20 and three spaced plates 21 mounted respectively between the metallic screen 14 and the envelope 10 and between the anode 18 and the reentrant tube 13 and around the screen 14 and the anode 18, with the nipples 22 and 23 fitting snugly in the depressions 25 and 26, with the plates flexed inwardly towards the surrounded members and having a major portion of the outer surfaces of

the plates 20 and 21 bearing against the inner walls of the envelope 10 and the reentrant tube 13 respectively, and with the rounded ends of the marginal portions of these plates contacting the metallic screen 14 and the anode 18 respectively. 5

With the above construction, it is apparent that there are substantially no line contacts between the bearing plates 20 and 21, and the surrounding elements 10 and 13, but there is a substantially large surface contact between these plates and their surrounding elements and further, that there are a plurality of spaced firm contacts between the surrounded elements 14 and 18 and the plates. Moreover this construction eliminates the necessity of forming threads on the element to be supported and eliminates also the employment of screws or bolts to secure the bearing plates on said elements.

Other advantages of my invention are that plates of any given size function efficiently even when employed with surrounding elements of substantially different internal diameters. Furthermore, the large surface contact obtained between the plates and the surrounding member provides a relatively "soft" or even frictional contact which serves to maintain the surrounded element, such as the anode 18 or screen 14, in position and allows the anode and screen to creep due to temperature changes, and still further, these plates can be efficiently employed with surrounding elements frequently found to be out of round.

These plates 20 and 21, the thickness of which may vary, and I have found that plates of this character measuring .012 inch in thickness serving my purpose in X-ray tubes, may be readily and economically manufactured. One of the methods which I have employed for this purpose consists in severing a sheet of molybdenum metal into blanks of appropriate size, thereafter subjecting the blanks to a forming operation, as between male and female dies of appropriate contours, whereby to properly shape the general contour of the blank and to form the nipples therein. The edges of the so formed plates may be rounded off if desired and the plates may be finally subjected to a suitable cleaning treatment, such as a run through an elevated temperature reducing atmosphere. 50

The thus finished plates are, of course, readily interchangeable and may be readily assembled in an X-ray tube in any convenient manner. Besides being interchangeable, these plates have another advantage of being readily reclaimed. 55

It has been found that X-ray tubes embodying my invention as before described may be readily and inexpensively manufactured to provide a rugged tube which will withstand shocks and jarring without cracking of the frangible members.

Having outlined my invention it is apparent that there may be many variations of the same without essentially departing from the nature and scope thereof as is set forth in the following claims:

What is claimed is:

1. An electrical device comprising an evacuated envelope, a cathode therein, a readily frangible member, another member having at least a portion of its surface spaced from and adjacent a portion of the surface of said frangible member, and a plurality of individual and separate resilient bearing means between said two members, each of said resilient means hav- 75

ing a longitudinal marginal portion curved inwardly and away from said frangible member, with the longitudinal edge of said marginal portion being located inwardly and away from said 5 frangible member and adjacent said other member, at least one of said resilient means being flexed around said other member and having the major portion of one of its surfaces bearing against a surface of the frangible member and its 10 opposite surface bearing against a surface of said other member.

2. An electrical device comprising an evacuated envelope, a plurality of electrodes therein, a readily frangible member surrounding and spaced 15 from the outer periphery of one of said electrodes, and a plurality of individual and separate spaced resilient plates between said electrode and said member with each of said plates bearing against said electrode, flexed there- 20 around and having the major portion of one of its surfaces in frictional contact with said member, said plates having their longitudinal edges located inwardly and away from said member.

3. An electrical device comprising a cathode, a 25 member surrounding the cathode of said device, a plurality of heavy elements disposed therein, with one of said elements spaced from and surrounded by said surrounding member, said surrounding member being frangible, and a plurality 30 of separate and individual spaced resilient plates mounted around said element and between said element and said frangible surrounding member, each of said resilient plates having portions thereof curved inwardly towards said element, 35 with the longitudinal edges of said plates being located out of contact with and away from said

frangible member, the major portion of one surface of said plate being in frictional contact with said frangible member, the opposite surface of said plate being in contact with said element.

4. An electrical device comprising a cathode, 5 a readily frangible member and a plurality of heavy elements disposed within and spaced from the inner periphery of said frangible member, a plurality of depressions in the outer periphery of one of said elements, a plurality of resilient 10 plates having means adapted to lie in said depressions, said plates located between said element and said readily frangible member, said plates having the major portions of the outer surfaces thereof in frictional contact with said frangible member, the inner surfaces of said plates contacting said element, said plates being flexed around said element, with the longitudinal edges being located away from and out of contact with 15 said frangible member. 20

5. In an X-ray tube, a readily frangible envelope having a plurality of relatively heavy elements spaced from and located within said envelope, a cathode within said envelope, one of said elements having a plurality of depressions on the 25 outer surface thereof, a plurality of individual resilient plates located between said element and said envelope, means on said plates located in said depressions, said plates being flexed around said element and having the major portion of the 30 outer surface thereof in frictional contact with said envelope, with the edges of said plates extending longitudinally of the envelope and being 35 out of contact with and located inwardly from said envelope. 35
